CLAIM

The ornamental design for a battery housing for industrial equipment, as shown and described.

DESCRIPTION

FIG. 1 is a front, right perspective view of a battery housing for industrial equipment disclosed herein.

FIG. 2 is a rear, left perspective view of the battery housing for industrial equipment of FIG. 1.

FIG. 3 is a right side view of the battery housing for industrial equipment of FIG. 1; and,

FIG. 4 is a top view of the battery housing for industrial equipment of FIG. 1.

The broken lines shown in the drawings are for the purpose of illustrating portions of the battery housing for industrial equipment that form no part of the claimed design.

The lighter solid lines denote surfaces and contours. Line shading is not surface ornamentation.
